(57) CLAIM

The ornamental design for a cup base with five lights, as shown and described.

DESCRIPTION

The file of this patent contains at least one photograph executed in color. Copies of this patent with color photographs will be provided by the Patent and Trademark Office upon request and payment of the necessary fee.

FIG. 1 is a perspective view of a cup base with five lights showing my new design;

FIG. 2 is a front elevational view thereof;

FIG. 3 is a rear elevational view thereof;

FIG. 4 is a top view of the cup base, showing an end-view of the top-most surface centrally superimposed on a view of the upper surface of the base; and,

FIG. 5 is view of the cup base as seen from the underside. The broken line showing of a cup is for illustrative purposes only and forms no part of the claimed design.
